UNITED STATES PATENT OFFICE.

MILLARD FILLMORE DERRICK, OF MONTREAL, QUEBEC, CANADA.

SUCTION GAS-PRODUCER.

1,107,917.

Specification of Letters Patent. Patented Aug. 18, 1914.

Application filed June 12, 1913. Serial No. 773,309.

To all whom it may concern:

Be it known that I, MILLARD FILLMORE DERRICK, a subject of the King of Great Britain and Ireland and the Isle of Man, 5 and resident of Montreal, Canada, have invented new and useful Improvements in Suction Gas-Producers, of which the following is a specification.

This invention has reference to and comprises improvements in suction gas producers in which the fuel is fed to a combustion chamber wherein the gas is generated, collected and conveyed to the engine which is to be operated thereby.

15 The invention consists in the provision of a suction gas producer of the underfeed type characterized by the fact that the whole of the fuel is continuously and uniformly under compression forced from the lower to the upper end of the combustion chamber by a helical conveyer extending the full diameter of said chamber and operating in a feed chamber situated directly below same. The ashes are discharged over 20 the top edge of the wall of the combustion chamber through water seals preferably being guided to said seals and between the said combustion chamber wall and an outer wall by angled plates. Air is passed through the 25 spindle of the helical conveyer into the combustion chamber and air may also be passed into said combustion chamber through the walls of same. It is preferred that the blades of the helical conveyer are formed of 30 increasing pitch and the wall of the combustion chamber tapered, that is, of increasing diameter from the lower to the upper end.

In order that my said invention and the 40 manner of carrying the same into effect or practice may be properly understood, I have hereunto appended two sheets of explanatory drawings in which—

Figure 1 is an elevation, partly in section, 45 of a suction gas producer constructed according to the improvements of this invention, while Figs. 2 and 3 are sectional plan views taken respectively on the lines 2—2 and 3—3 of Fig. 1.

50 Referring to these drawings: According to the improvements of this invention the fuel is fed to the generating chamber by a helical conveyer extending the full diameter of the lower end of same in a continuous 55 manner, from below the same, the entry of

fresh fuel automatically displacing that fuel which has given up its quota of gas, and discharging the same over the top edge of the generating chamber wall currents of air being forced through the mass from the bottom center and or sides and with the gas, 60 first passing through the fresh fuel and lastly through the depleted fuel, from which it is conveyed to the engine. The depleted fuel being still heated frees the vapor 65 from tar, etc., and thereby the engine is protected from the injurious effects resultant from such gummy substances.

In carrying the improvements of this invention into effect or practice the suction 70 gas generator comprises a suitably supported feed funnel or chamber *a* provided with coal hoppers or chutes *b*, a generating chamber *c* being preferably supported upon the top of the chamber *a*. A gas collecting 75 dome *d* is located above the generating chamber *c* and a series of water or other suitable seals *e* is provided at the bottom of the dome *d*. A pipe *f* leads from the dome *d* to the engine. The upper end of the feed 80 chamber *a* is preferably of the same diameter as the lower end of the chamber *c* and within the chamber *a* a fuel conveyer in the form of a helical ram *g* is located. The diameter of this conveyer *g* extends the full 85 distance of the chamber *a* and preferably the pitch of said conveyer *g*, increases from its lower end so as to prevent or minimize clogging. This ram is rotatively mounted and adapted to be continuously operated, 90 preferably by the worm and wheel gearing *h*. Currents of air are directed into the generating chamber *c* from the bottom, center and (or) sides, these currents being, for example, conveyed through the spindle *i* of 95 the ram *g* and directed into the chamber *c* through orifices *n* at the end of spindle *i* or (and) also directed from the sides of the chamber as shown by the passage *j*.

The wall of the chamber *c* is preferably 100 of tapered formation, that is, the chamber *c* is of greater diameter at its upper end than it is at its lower end and a space *k* is formed between the wall of the chamber *c* and the lower portion *l* of the wall of the dome *d*. 105 Plates *m* are preferably fitted into this space *k* so as to guide the discharge from the chamber into the water seals *e* and these plates *m* are preferably fitted in pairs with their upper ends meeting and their lower 110

ends apart like an inverted V formation. There are preferably four pairs of plates *m* and a water seal is arranged between each pair.

5 The fuel is fed from the hoppers *b* and is conveyed upwardly and uniformly under compression by the continuously operating spiral ram *g* to the generating chamber *c*, the air currents passing through the charge 10 which, as fresh fuel is brought to the chamber, is freed from its gas and gradually forced upward until it is crowded from the top of the generating chamber and falls down the inclined plates *m* into the water 15 seals *e* and so disposed of. The gas is collected in the dome *d* and conveyed to the engine by the pipe *f* leading from the dome.

The hoppers may be of any capacity and with the automatic cleaning of the generator chamber and the continuous operation 20 of the spiral ram, the present generator may be run continuously, thus doing away with alternately working generators.

I claim:—

25 1. The combination in a gas producer of a vertical feed casing; means for delivering fuel thereto; a vertical conveying screw in said casing; a generating chamber vertically above the feed casing and forming a continuation thereof; a gas collecting dome above said generating chamber and extending down around the sides thereof; a series of water seals placed to receive material discharged over the top of the combustion chamber; and deflecting plates between each two adjacent water seals.

2. The combination in a gas producer of a vertical feed casing; means for conducting material thereto; a generating chamber vertically above the feed casing; a hollow spindle in said casing connected to a source of air under pressure and having outlets for delivering air to said chamber; a conveying screw on said spindle within the casing; a gas collecting dome; and water seals placed to receive ashes delivered from said generating chamber.

3. The combination in a gas producer of a vertical feed casing; means for delivering fuel to the lower end thereof; a vertical conveying screw in said casing; a generating

chamber vertically above the feed casing and forming a continuation thereof; an annular conduit surrounding the casing adjacent its point of connection with the generating 55 chamber and connected to a source of air under pressure, there being outlets from said conduit into the lower part of said chamber; a gas collecting dome over the generating chamber and extending down around the 60 sides thereof; with water seals placed to receive material discharged over the top edge of the generating chamber.

4. In a gas producer the combination comprising the feed funnel *a*, the combustion 65 chamber *c* having air supplying passages, the ram *g*, a conduit for supplying air to the combustion chamber having orifices *n*, hoppers *b*, and a series of water seals *e* all constructed and arranged substantially as and 70 for the purposes herein set forth.

5. The combination in a gas producer of a vertically extending feed casing; means for introducing fuel to the bottom of said casing; a generating chamber forming a 75 continuation of the feed casing; a gas collecting dome mounted over the generating chamber and extending down around the same; water seals placed to receive material 80 discharged over the top edge of the generating chamber; a conveying screw mounted in the feed casing and having its blades of greater pitch at its upper end than at its lower end; with means for rotating said screw on a vertical axis.

6. The combination in a gas producer of a gas collecting dome having a lower portion constituting an outer wall; a water seal for the lower edge of said wall; a generating chamber within and spaced away from the 90 wall of said dome; with angle plates fitted in the space between the wall and the sides of said chamber and mounted to discharge into the water seal the material delivered over the upper edge of the chamber.

In testimony whereof I have affixed my signature in presence of two witnesses.

MILLARD FILLMORE DERRICK.
